CLAIM

The ornamental design for a transparent egg container as shown and described.

DESCRIPTION

FIG. 1 is a top perspective view of the transparent egg container according to the invention.

FIG. 2 is a front view of the transparent egg container of FIG. 1.

FIG. 3 is a rear view of the transparent egg container of FIG. 1.

FIG. 4 is a top view of the transparent egg container of FIG. 1.

FIG. 5 is a bottom view of the transparent egg container of FIG. 1.

FIG. 6 is a left side view of the transparent egg container of FIG. 1.

FIG. 7 is a right side view of the transparent egg container of FIG. 1.

FIG. 8 is a bottom perspective view of the transparent egg container of FIG. 1.

FIG. 9 is a top perspective view of the transparent egg container of FIG. 1 showing eggs inside the container in dashed lines.

FIG. 10 is a cross-sectional view of the transparent egg container of FIG. 1 taken along lines 10-10 in FIG. 4; and, FIG. 11 is a cross-sectional view of the transparent egg container of FIG. 1 taken along lines 11-11 in FIG. 4.

The evenly spaced broken lines represent parts of the article, exemplary environment, and the edge of break lines. None of the broken lines form a part of the claimed design. The zig-zag break lines represent symbolic breaks in the article. The appearance of any portion of the article between the break lines forms no part of the claimed design.
